US0D1045318S

(12) **United States Design Patent** (10) **Patent No.:** **US D1,045,318 S**
(45) **Date of Patent:** **** Oct. 1, 2024**

(54) **CONVEYOR WIDTH ADJUSTER**

(71) Applicant: **DYCO, INC.**, Bloomsburg, PA (US)

(72) Inventors: **Peter D. Yohe**, Bloomsburg, PA (US);
Ronald H. Cordingly, Berwick, PA (US);
Thomas M. Zurewich, Orangeville, PA (US)

(73) Assignee: **DYCO, Inc.**, Bloomsburg, PA (US)

(**) Term: **15 Years**

(21) Appl. No.: **29/796,692**

(22) Filed: **Jun. 25, 2021**

(51) LOC (14) Cl. **12-05**
(52) U.S. Cl.
USPC **D34/29**

(58) **Field of Classification Search**

USPC **D34/29, 35**
CPC **B65G 21/2072; B65G 21/14; B65G 2201/02; B65G 2201/0235; B65G 17/08; B65G 47/66; B65G 47/52**

(57) **CLAIM**

The ornamental design for a conveyor width adjuster, as shown and described.

DESCRIPTION

FIG. 1 is a top-front perspective view of a conveyor width adjuster, showing the design;

FIG. 2 is a top plan view thereof;

FIG. 3 is a bottom plan view thereof;

FIG. 4 is a front view, the rear view being a mirror image thereof; and,

FIG. 5 is a left view, the right view being a mirror image thereof.

The broken lines in the figures show portions of the conveyor width adjuster which form no part of the claimed design.

1 Claim, 5 Drawing Sheets
